UNITED STATES PATENT OFFICE

CARL BUSCH THORNE, OF HAWKESBURY, ONTARIO, CANADA

PULP STORING AND MIXING MACHINE

Application filed March 22, 1929. Serial No. 349,168.

The invention relates to a pulp storing and mixing machine, as described in the present specification and illustrated in the accompanying drawings that form part of the same.

6 The invention consists essentially of the novel features of construction pointed out broadly and specifically in the claims for novelty following a description containing an explanation in detail of an acceptable form 10 of the invention.

The objects of the invention are to insure uniformity in the various manufactures from pulp as in any one mill there cannot possibly be any guarantee that the product of 15 one digester will be the same as the product of another digester in fact there is bound to be a difference and consequently no surety of evenness in the massed product of a day's operation; to maintain uniformity in pulp 20 mills particularly in the production of pulp at high density so that the slightest difference in the cooking of the pulp in one digester will be lost in the distribution of the pulp from this digester throughout the products 25 of the other digesters; to increase the values of silk, paper and other manufactures made from wood or other pulp material; to accomplish this method of mixing the pulp at a low cost and thereby avoid any additional expense in the production of goods from pulp; 30 and generally to provide a reliable and simple means of evening the product of a mill.

In the drawings, Figure 1 is a vertical sectional view of the partition tank forming receptacles for the pulp resulting from the day's 35 operation.

Figure 2 is a plan view of the tank from above.

Figure 3 is a plan view of the bottom of 40 the tank.

Figure 4 is an enlarged plan view of the distributor and the feed mechanism.

Figure 5 is a cross sectional view of the distributor as illustrated in Figure 4.

45 Figure 6 is an enlarged detail of the electrical and mechanical device for automatically operating the discharge hopper.

Figure 7 is an enlarged fragmentary detail of the self adjusting ratchet showing the teeth in elevation.

Figure 8 is a fragmentary detail of the ratchet teeth illustrated in Figure 7.

Figure 9 is a plan view showing the detail of the automatically operating electric switch.

55 Figure 10 is a sectional detail of the switch illustrated in Figure 9.

Like numerals of reference indicate corresponding parts in the various figures.

60 Referring to the drawings, the tank is indicated by the numeral 15 and this tank is divided into as many compartments as may be desired, and is here shown as divided into four receptacles 16, 17, 18 and 19 by the vertical partitions 20. This tank is suitably suspended by vertical beams from a superstructure not shown in the drawings or described in detail as many different forms of suspensions or supports and like framing are common in pulp mills to support vats or tanks slightly above the bottom 21 to form the annular opening 22 for the scraper arm 23.

65 The bottom 21 supported on the posts 24 is inclined inwardly to the annular discharge opening 25 surrounding the center piece 26 inclined to said opening 25. The bottom 21 is flanged upwardly at 27 towards the wall of the tank 15 and beyond this flange 27 is 70 recessed to form the annular drain 28.

75 The bottom 21 is dropped slightly around the opening 25 and extended inwardly at 29 and from this extension the tip 30 projects downwardly, said extension 29 projecting inwardly under the center piece 26 from all sides and forming under said center piece a central discharge opening 31 at one side of which the tip 30 forms a guard across the endless conveyer operating under the bottom and extending therebeyond to the elevator 33.

80 The arm 23 is fixedly mounted on the pin 34 journalled in the center piece 26 and the plow shaped scrapers 35 are secured to said arm and extend into the vicinity of the inclined bottom both on the inward and outward inclines and downwardly therebetween.

85 The short arm 36 is also mounted on the pin 35 below the center piece 26 at an angular position in relation to the arm 23 and carries the scrapers 37 sweeping the floor of the extension 29.

The arm 23 is driven by the motor 38 mounted on the base 39 and from this base depends the bracket 40 forming a bearing of the flanged wheels 41 running on the circular rail 42 around the tank 15, the motor 38 drives the sprocket 43 through the reducing gear 44 and the chain 45 is threaded through the driven sprocket 43 and the idle sprocket 46 both suitably mounted on the base 39, the 5 said chain 45 encircles the bottom 21 and engages said bottom at intervals through the flights 47 therefore the sprockets travel on the chain, not the chain on the sprockets and as the base 39 is rigidly secured to the outer 10 end of the arm 23 the said arm continuously scrapes the inclined bottom surfaces of the tank and coincidentally the short arm scrapers sweep the floor of the extension under the center piece 26 all tending towards thorough- 15 ly mixing the discharges from the receptacles 16, 17, 18 and 19 as at each operation only a comparatively thin layer at the finish of each revolution draws the scraping from each discharge together so that in the final dis- 20 charge the products of the several digesters are thoroughly mixed to form a common product and this common product is delivered onto the conveyor 32 and conveyed to the elevator 33.

30 The elevator 33 dumps this material into a proportioning apparatus 48 which is formed of the drum shaped casing 49 having outlets 50 and 51 through the bottom from the central portion and between the center and the 35 edge respectively the spout 52 projecting downwardly from the outlet 50 and directing the material on to the conveyor belt 59 and the spout 53 projecting downwardly from the outlet 51 and directing the material into 40 the rotating hopper 54 centrally arranged over the tank 15.

The rotor 55 of the proportioning apparatus is divided into a plurality of compartments by the radial partitions 56, these compartments being open from top and bottom and passing with the continuous rotation clockwise of the rotor 55 under the scraper 57 which deposits a proportion of the pulp in the center 58 of the casing from which it is 45 discharged from the spout 53 to the storage tank, the remainder in the several pockets passing through the outlet 51 into the hopper 54 from which it is returned through the conveyor 59 to one or other of the receptacles 55 16, 17, 18 or 19.

The conveyor 60 is also directed to the hopper 54 and is the original feeder to the tank 15.

The hopper 54 is fixedly mounted on the 60 vertical shaft 61 extending upwardly from the center of the vertical partitions 20.

The coacting gear mechanism 62 between the shafts 61 and 63 forms the means of operating the hopper 54 so that it would be directed consecutively and periodically to the

receptacles 16, 17, 18 and 19. The intermittent sprocket 64 is mounted on the shaft 63 and is driven by the pawl 65 pivotally connected through the link 66 to the driven crank wheel 67, therefore this pawl is continuously reciprocating and in reciprocation engages the teeth 68 which are at intervals interrupted by the spaces 69.

These spaces are periodically closed by the pivotally mounted teeth 70; each tooth 70 is mounted on a pivot 71 and is formed with an extending tail 72 and a forwardly extending lug 73 fitting into a notch 74 ending the neighbouring tooth. The tail 72 is engaged by a roller 75 at the lower end of the pin 76, this pin 76 being pivotally secured to a rocker arm 77 in turn pivotally secured to the core 78 of the solenoid 79, therefore when the solenoid is energized the core is inwardly drawn and thus through the rocker arm and pivoted pin exerts pressure on the tail of the tooth and swings said tooth into line so that it is disengaged by the pawl and thereby bridges the distance to the next tooth and then continues the operation.

When this apparatus is in proper operation the four receptacles will always be filled to different levels, one quite full, the next one three quarters full, the next one half full, the fourth one one quarter full, consequently some means is necessary to regulate the operation of the intermittent sprocket.

In each receptacle at the upper end a gravity electrical switch arm 80 leans outwardly and is operated to close an electrical switch 81 and as this switch arm is hinged at 82 to the tank wall, the weight of the pulp as it reaches and covers the arm will readily close the switch which is preferably of the mercury type.

The electric distributor 83 is operated by the coacting gear mechanism 84 operatively connecting the vertical shaft 61, and the distributor shaft 85, insuring the rotation of the latter at the same speed as the hopper 54.

There are four rings on the distributor shafts corresponding to the four receptacles and on each ring there is a brass contact 86, each ring being set at ninety degrees from the preceding ring so that only one contact can be made at a time. These contact rings are severally connected to the mercury switches and there is a common connection to the solenoid and a connection from the source of power to the solenoid and to the switches, consequently the filling of each receptacle insures the energization of the solenoid and the operation of a pivoted tooth as explained and it may be said that the tail 72 of each tooth operates between the stops 87 and 88 from the ratchet wheel.

In the operation of this invention, the general feed conveyor brings the pulp from the mill to the rotary hopper 54 and the several receptacles are filled in the proportions

named, the operation then is practically continuous for the amount of material is regulated, a certain quantity is constantly swept to the general discharge through the bottom and conveyed to the elevator, where it is elevated to the proportioning apparatus and partly returned to the tank and partly discharged finally and by this means there is positive assurance of the thorough mixing of the products from the several digesters of the mill.

What I claim is:—

1. In a storing and mixing apparatus, a plurality of receptacles, means for gathering the products from said receptacles and means for proportioning the combined discharges for return to the receptacles and for final discharge.

2. In a storing and mixing apparatus, a plurality of grouped receptacles having gravity discharges, means for gathering these discharges to a common discharge, means for elevating the common discharge, means for proportioning the common discharge, means for distributing a portion throughout said grouped receptacles, and means for effecting the final discharge of the remaining portion.

3. In a storing and mixing apparatus, a plurality of grouped receptacles having a common bottom and a communicating discharge opening directed to a common discharge opening, means for elevating the common discharge and means for redistributing a portion of the elevated product throughout the receptacles and forwarding the remainder to the final discharge.

4. In a storing and mixing apparatus, a plurality of grouped receptacles having a common bottom and an opening in said bottom leading from the several receptacles and to a central opening under the central part of said bottom, a conveyer under said central opening, means for gathering the products to said central opening means for elevating the combined products, and means for redistributing a portion of the combined products throughout the receptacles and forwarding the remainder to the final discharge.

5. In a storing and mixing apparatus, a tank forming a plurality of grouped receptacles suspended above a common bottom and forming an annular opening therebetween and having in said bottom a discharge opening common to said receptacles and a central discharge opening connected to the aforesaid discharge opening, means extending through said annular opening for gathering the products from the several receptacles to said central opening, a conveyor under said central opening, an elevating conveyor connected to said conveyor and a proportioning apparatus distributing part of the combined products to said receptacles and part to the final discharge.

6. In a storing and mixing apparatus, a

tank forming a plurality of grouped receptacles and suspended over a common bottom to form between said bottom and the tank wall an annular opening immediately above an annular drain in said bottom, said bottom having a discharge opening common to said receptacle and a central discharge opening common to the aforesaid discharge openings, an arm having scrapers attached thereto sweeping the bottom of said tank and extending through said annular opening beyond said tank, means for rotating said scraper arm, means for elevating the product from said central opening and a proportioning apparatus for distributing part of the combined products to said receptacles and part to the final discharge.

7. In a storing and mixing apparatus, a tank forming a plurality of grouped receptacles and suspended over a common bottom to form between said bottom and the tank wall an annular opening immediately above an annular drain in said bottom, said bottom having a discharge opening common to said receptacle and a central discharge opening common to the aforesaid discharge openings, a central rotatable pin mounted in said bottom, a long arm having scrapers and extending through said annular opening and fixedly mounted on said pin, a short arm fixedly mounted on said pin and having scrapers operating on lower level than the aforesaid scrapers, a carriage rigidly secured to the outer end of said long arm and travelling on a rail, a chain and sprocket mechanism and driving member on said base and encircling said tank, means for elevating the product and distributing means at the upper end, means for elevating the product from said central opening and a proportioning apparatus for distributing part of the combined products to said receptacles and part to the final discharge.

8. In a storing and mixing apparatus, a plurality of grouped receptacles having individual discharges and a discharge common to said individual discharges, means for conveying and elevating the combined products and means for proportioning the combined products including devices for distributing the product throughout the receptacles and separating a portion for final discharge.

9. In a storing and mixing apparatus, a plurality of grouped receptacles having individual discharges and a discharge common to said individual discharges, means for conveying and elevating the combined products and means for proportioning the combined products, including a cylindrical casing having a final discharge outlet and a redistribution outlet and a compartment rotor and scraper feeding said outlets.

10. In a storing and mixing apparatus, a plurality of grouped receptacles having individual discharges and a discharge common

- to said individual discharges, means for conveying and elevating the combined products and means for proportioning the combined products, including a casing having outlet chutes therefrom to a final discharge and to a rotatable hopper forming a distributor to the several receptacles. .
11. In a storing and mixing apparatus, a plurality of grouped receptacles having individual discharges and a discharge common to said individual discharges, means for conveying and elevating the combined products and means for proportioning the combined products, including a rotor partitioned to form a plurality of radial passages there-around and suitably driven and rotating in a casing having an outlet open and chute under the path of said passages and a central outlet chamber over a chute effecting a final discharge.
12. In a storing and mixing apparatus, a plurality of grouped receptacles having individual discharges and a discharge common to said individual discharges, means for conveying and elevating the combined products and means for proportioning the combined products, including a continuously rotating member having passages formed by radial partitions and bounding a central chamber and turning in a drum casing having outlets from said passages and chamber and supporting a scraper skimming said passages of product delivered to said chamber and a rotating hopper having a chute consecutively directed to said receptacles.
13. In a storing and mixing apparatus, a plurality of grouped receptacles having individual discharges and a discharge common to said individual discharges, means for conveying and elevating the combined products, a rotatable hopper having a chute directed to said receptacles by selection, means for rotating said hopper and means for delivering the products to said hopper.
14. In a storing and mixing apparatus, a plurality of grouped receptacles having individual discharges and a discharge common to said individual discharges, means for conveying and elevating the combined products, a rotatable hopper fixedly mounted on a vertical shaft centrally mounted in relation to said receptacles, a ratchet driving mechanism operatively connected with said shaft and having an intermittent sprocket electrically controlled and automatically turning said hopper to direct the products respectively to the receptacles and means for delivering the products to said hopper.
15. In a storing and mixing apparatus, a plurality of grouped receptacles having individual discharges and a discharge common to said individual discharges, means for conveying and elevating the combined products, a vertical shaft operatively connected to a ratchet driving mechanism containing an in- intermittent ratchet wheel having pivotally mounted teeth at intervals in the fixed teeth and a reciprocating pawl, a solenoid having its core operatively connected with each pivoted tooth in turn, a gravity cut out in each receptacle in the electrical connections, to said solenoid operated by the rise and fall of the product in the receptacle, a hopper having a chute directed to the selected receptacle and fixedly mounted on said vertical shaft and means for delivering product to said hopper.
16. In a storing and mixing apparatus, a plurality of receptacles having a common discharge, means for returning discharged product to the several receptacles and means for withdrawing a portion of the returning product and finally discharging said portion.
17. A storing and mixing apparatus, comprising tanks having a common discharge for differently classifiable products and means for mixing the withdrawal of the finished mixture.
18. In devices of the kind described, means for storing manufactured products from various sources of production, means for withdrawing them to a common collection, means for remixing and means for continuously withdrawing a portion for the manufacturers.
- Signed at Montreal, Canada, this 29th day of January, 1929.
